L. C. BAYLES

BLOWING DEVICE

Filed Oct. 19, 1925

INVENTOR.
Lewis C. Bayles.
BY Herbert G. Ogden
HIS ATTORNEY.

UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

BLOWING DEVICE.

Application filed October 19, 1925. Serial No. 63,260.

This invention relates to rock drills, but more particularly to a blowing device for fluid actuated rock drills of the hammer type.

5 The objects of the invention are to selectively admit an uninterrupted supply of pressure fluid under full line pressure to the drill steel for cleansing the drilled hole and to hold the valve and the piston immovable 10 while such pressure fluid is passing through the drill steel.

Other objects will appear hereinafter.

The invention consists of the combinations of elements, features of construction, and 15 arrangement of parts having the general mode of operation, substantially as herein-after described and more particularly pointed out in the appended claims and illustrated in the accompanying drawings, in 20 which—

Figure 1 is a longitudinal diagrammatic view in section of so much of a rock drill as will serve to illustrate the invention.

Figure 2 is a view similar to Figure 1 25 showing the reciprocating parts in another position, and

Figure 3 is a view similar to Figures 1 and 2 showing the manner in which pressure fluid is admitted to the drill steel.

30 Referring to the drawings, the invention is shown embodied in a drill having a cylinder A provided with a reciprocating hammer piston B. A front head C is arranged at the front end of the cylinder A and is centralized with respect thereto by a front cylinder washer D. The cylinder A and the front head C are preferably held in operative position by the usual side bolts (not shown).

40 Disposed within the front head C is a rotatable chuck E having ribs F which cooperate with flutes G formed on an extension H of the piston B to prevent relative rotation between said piston and the chuck E. 45 The front end of the chuck E is bored as at J to receive a drill steel K and to hold said drill steel against rotation with respect thereto.

In order to impart rotary movement to 50 the piston B and consequently the drill steel K for keeping the drill steel free within the drill hole, a rifle bar L engages the piston B in the usual manner and may be held in any convenient manner against rotation while 55 the piston is traveling in one direction and

to permit rotation of the rifle bar with the piston during the opposite stroke of the piston. The rifle bar L in this instance is adapted to project through a back cylinder washer O fixed in the rear end of the cylinder A to form a closure for said cylinder, the entire construction not being shown. A valve chest P is in this instance arranged longitudinally of the cylinder A and has a valve chamber Q in which chamber is arranged a spool type distributing valve R, the type of valve here illustrated is like that covered in the copending application of W. A. Smith, Serial No. 23,181, filed, April 15, 1925, although any suitable valve in which 60 kicker ports are employed for actuating the valve may be used. The valve shown has a central head S which controls a central inlet port T and has end heads U and V for controlling the main exhaust port W and X 65 respectively formed on opposite sides of the inlet port T. The ends of the chamber Q are closed by bushings Y which also serve as stops for limiting the travel of the valve R and form valve chest spaces Y' and Y² between the bushings and the valve end heads. Motive fluid for actuating the piston is supplied to the rear and front ends of the cylinder through supply passages Z and b respectively communicating with the valve chamber Q on opposite sides of the central inlet port T. 70

Usually in drills employing valves of the type indicated in the drawings, kicker ports are used for controlling the action of the 75 valve. Such kicker ports may be crossed as in the present instance in which a kicker port c leading from a point rearward of the center of the cylinder A communicates with the front end space Y² of the valve chamber Q to admit pressure fluid to said front end for throwing the valve rearwardly. A second kicker port or passage d communicating with the cylinder A at a point forwardly of its center extends to the rear end space Y' 80 of the valve chamber Q to admit pressure fluid to said rear end for throwing the valve forwardly.

A hollow longitudinal bore e formed in the valve chest in this instance contains an 85 auxiliary valve f shown as a slide valve although it could be of any suitable form and construction for establishing communication between the supply of pressure fluid and one valve space Y² and at the same time 90

to open the opposed valve space Y' to atmosphere, so that the valve is held at one end of its travel and the piston is held at the rearward end of its stroke to permit pressure fluid to blow down the drill steel from the front end of the cylinder.

A normally closed auxiliary port g connects the valve chest space Y^2 with any point supplied with live pressure fluid, as

- 5 for instance the supply port b , and a groove h in the valve f opens communication through said auxiliary port g , as shown in Figure 3. Two auxiliary ports j and k are adapted to connect the valve chest space Y' 15 with atmosphere through the exhaust port W when placed in communication by the groove o in the valve f . The valve is provided with the head or handle p and the re-tracting spring q at the opposite end.

- 10 20 In the operation of the device, the hammer piston B functions as usual and as described in the said copending application, Serial No. 23,181, when the auxiliary valve is in the retracted position indicated in Figures 1 and 2. When the valve f is forced inwardly against the spring q as in Figure 25 3, the kicker ports c and d are not disturbed, but live pressure fluid is continuously supplied to the valve chest space Y^2 30 to hold the valve in rearward position, and the opposite valve chest space is vented directly to atmosphere through the ports j and k and exhaust port W , so that the pressure in said space Y' is substantially 35 zero. The live pressure fluid supplied to the forward end of the cylinder A holds the piston in rearward position and at the same time blows continuously down the piston flutes and through the hollow drill 40 steel for cleansing purposes.

I claim:—

1. In a fluid actuated rock drill of the hammer type, the combination of a cylinder and reciprocating piston, a valve chest and 45 distributing valve therein controlling both the supply and exhaust of pressure fluid for the cylinder, valve actuating ports between opposed spaces in the valve chest and the

cylinder bore for supplying pressure fluid for actuating the valve, and means for admitting pressure fluid to one valve chest space and for establishing communication between the opposed space and the atmosphere, whereby the valve is held at one end of its travel and the piston is held at the rearward end of its stroke to permit blowing to be effected.

2. In a fluid actuated rock drill of the hammer type, the combination of a cylinder and reciprocating piston, a valve chest and distributing valve therein controlling both the supply and exhaust of pressure fluid for the cylinder, valve actuating ports between opposed spaces in the valve chest and the cylinder bore for supplying pressure fluid for actuating the valve, and an auxiliary valve for establishing communication between one valve chest space and the inlet supply of pressure fluid and for opening the other opposed space to atmosphere, whereby the valve is held at one end of its travel and the piston is held at the rearward end of its stroke to permit blowing to be effected.

3. In a fluid actuated rock drill of the hammer type, the combination of a cylinder and reciprocating piston, a valve chest and distributing valve therein controlling both the supply and exhaust of pressure fluid for the cylinder, valve actuating ports between opposed spaces in the valve chest and the cylinder bore for supplying pressure fluid for actuating the valve, an auxiliary pressure fluid port for one of said valve chest spaces, and two ports for the other valve chest space, one of which ports leads to atmosphere, and an auxiliary valve for opening said auxiliary pressure fluid port and for connecting said two ports, whereby the valve is held at one end of its travel and the piston is held at the rearward end of its stroke to permit blowing to be effected.

In testimony whereof I have signed this specification.

LEWIS C. BAYLES.
